UNITED STATES PATENT OFFICE.

HENRY W. BROWN, OF CAMBRIDGE, MASSACHUSETTS.

HYDRAULIC DREDGING APPARATUS.

SPECIFICATION forming part of Letters Patent No. 441,055, dated November 18, 1890.

Application filed April 17, 1890. Serial No. 348,343. (No model.)

To all whom it may concern:

Be it known that I, HENRY W. BROWN, a citizen of the United States, and a resident of Cambridge, in the county of Middlesex and State of Massachusetts, have invented new and useful Improvements in Hydraulic Dredging Apparatus, of which the following, taken in connection with the accompanying drawings, is a specification.

This invention relates to improvements in hydraulic dredging apparatus, and it is carried out as follows, reference being had to the accompanying drawings, wherein—

Figure 1 represents a plan view of the invention. Fig. 2 represents a side elevation of the same, parts of which are shown in section. Fig. 3 represents an end view as seen from X in Fig. 1. Fig. 4 represents a detail plan view of the mechanism for raising and lowering the agitator, for rotating the latter, for oscillating the frame, and for swinging the telescopic suction-pipes to one side. Fig. 5 represents a vertical longitudinal section of the rotary agitator and the telescopic suction-pipes. Fig. 6 represents a detail plan view of the rotary conical carrying-hood. Fig. 7 represents a cross-section on the line Y Y shown in Fig. 5. Fig. 8 represents a cross-section on the line Z Z, also shown in Fig. 5. Fig. 9 represents a detail side elevation of the rotary agitator, a portion of which is shown in section. Fig. 10 represents detail views of the upper and lower agitator blades or knives. Fig. 11 represents a detail plan view of the ring or wheel to which the agitator shaft and knives are attached. Fig. 12 represents a detail plan view of the rotary conical suction-hood, showing a portion of the aforesaid wheel below it; and Fig. 13 represents detail views of the hub and cap-plate, by means of which the aforesaid wheel or ring is secured to the rotary agitator-shaft.

Similar letters refer to similar parts wherever they occur on the different parts of the drawings.

In carrying out my invention I make use of a dredging-boat A of suitable size, which boat has a semicircular end A'. A'' is the deck of the said dredging-boat, as shown in Figs. 1, 2, and 3. At M' on said deck is pivoted the oscillating frame B, which carries

the suction-pipe, the rotary agitator, and the telescopic pipes leading from the agitator to the horizontal suction-pipe carried by the oscillating frame.

The rotary agitator is constructed as follows: It consists of a conical hood or conveyer C upon its upper and lower ends, as shown in Fig. 5, and having attached to the periphery of its lower end a ring C', provided with radial arms C'' C'', as shown in Figs. 5, 9, 11, and 12. To the central portion of said arms C'' of the ring C' is attached the upwardly-projecting vertical shaft C³, which is preferably secured to said arms C'' by means of a hub C⁴, (shown in detail in Fig. 13,) which hub is attached to the shaft C³ by its recesses C⁵ C⁵ in its under side for receiving the central portions of the rotary arms C'' C'', which are secured to the said hub C⁴ by means of a plate or disk C⁶, (shown in Fig. 13,) and suitable bolts or fastening-screws, by which the hub C⁴, disk C⁶, and arms C'' C'' of the ring C' are firmly jointed. I wish, however, to state that the vertical shaft C³ may be secured to the ring C' in any other suitable manner without departing from the essence of my invention.

To the ring C' are secured a series of outwardly-projecting grooved cutters or agitator-blades D D, preferably provided in their upper ends with notches d d, (shown in Fig. 10,) adapted to receive and be held on the rotary ring C'. The cutters D D are secured in an adjustable manner to the said ring C' by means of suitable fastening-bolts, as shown in the drawings. To the said ring C' are also secured a series of upwardly-projecting curved cutters or agitator-blades D' D', having notched recesses d' d' in their lower ends adapted to receive the ring C' and to be secured to the latter in an adjustable manner by means of suitable fastening-bolts, as shown.

The upper ends of the cutter or agitator-blades D' D' are secured together by means of an upper ring D'', as shown in Figs. 2, 3, 5, and 9.

To the upper surface of the conical conveyer C are secured or made in one piece with it a series of curved wings or ribs C' C', the object of which is to clear the top of the rotary conical conveyer C from any matters or débris that

may fall upon it during the dredging operation and to force such matters outward to enable it to be drawn up through from the under side of the said conical conveyer by the suction-power of the hydraulic pump, herein-after to be described.

The upper and lower cutter-blades D' D' are made convex in shape, so that they will commence to cut with their middle portions 10 against the banking that is to be dredged, thus preventing the whole of the vertical extent or length of said knives from being brought simultaneously against the banking, and thus preventing their being accidentally 15 broken.

The upper end of the conical conveyer C is guided or journaled at C⁸, as shown in Figs. 5 and 9, in a recess in the lower end of the stationary mouth E of the telescopic suction-pipes. The upper end of the pipe E is connected to the valve-box E', in which is located 20 a suitable feed-valve E'', loosely pivoted at E³ (shown in Fig. 5) for the purpose of holding the water and dredging material in the suction-pipes above said valve-chamber when 25 the hydraulic and centrifugal suction-pump is at rest.

E⁴ is a vertical bearing on one side of the valve-box E', as shown in Fig. 5, in which the 30 lower end of the agitator-shaft C³ is journaled, the said bearing being preferably provided with a lignum-vitae bearing-surface e, as shown in Fig. 5; but, if so desired, any other suitable material may be used within the said bearing E⁴ without departing from the spirit 35 of my invention.

C⁹ is what is called a "dirt-collar," secured to the rotary agitator-shaft C³ above the correspondingly-shaped collar secured to the top 40 of the bearing E⁴, as shown in Fig. 5, serving in part as a support for the shaft C³ and partly as a means for preventing the dirt and grit from entering the bearing E⁴.

To the top of the valve-box E' is secured a 45 hollow pipe F, and within the same is vertically adjustable the telescopic pipes F', and within the latter is also vertically adjustable a similar telescopic pipe F'', which pipes are to be provided with suitable packings to effect a tight joint between them, as they are extended or closed, and provided with suitable stop pins or collars to cause them to move together as they are being extended or closed together, as is common in telescopic-tube devices.

In Fig. 5 of the drawings I have shown only 50 two movable telescopic sections F' and F''; but it will readily be seen that I may use any suitable number of such telescopic pipes, according to the depth to which the dredging is to be carried. To one side of the stationary pipe F is secured a bearing F⁸, in which the upper end of the rotary agitator-shaft C³ is journaled, the latter being preferably provided in its upper end with a clutch or polygonal socket C¹⁰, adapted to receive the correspondingly-shaped lower end of the driving-

shaft G, (shown in Fig. 5,) and to be secured to the same by means of a pin or other suitable connecting devices. To the upper end 70 of the telescopic pipe F' is secured a bearing F⁴, in which the lower end of the driving-shaft G is journaled, as shown in Fig. 5. The telescopic pipes F, F', and F'' are preferably made four-sided; but they may be made of 75 any other desired section without departing from the essence of my invention.

E⁵ E⁵ (shown in Fig. 3 are) perforated ears or projections on two opposite sides of the valve-chamber E', to which the lower ends 80 of the ropes or chains are attached, by which the agitator is raised and lowered or swung to one side of the scow or boat, as will hereinafter be more fully shown and described.

The upper end of the inner section F'' of 85 the vertical telescopic pipes is attached in a suitable manner to an elbow-pipe F⁵, (shown in Fig. 2,) the horizontal end of which is adapted to turn in a stuffing-box joint on the horizontal suction-pipe F⁶, as shown at F⁷ in 90 said Fig. 2. To the outer end of the elbow F⁵ is secured in a suitable manner a vertical bearing F⁸, in which the vertical agitator driving-shaft G is journaled, said shaft having a number of vertical grooves g, to which 95 is splined a beveled gear G' in such a manner that said gear may be rotated so as to impart a rotary motion to the shaft G, with freedom for the latter to move up and down on said gear during the raising and lowering 100 of the rotary agitator. The inner end of the horizontal suction-pipe F⁶ is secured to an elbow-pipe F⁹, the lower end of which turns in a stuffing-box joint F¹⁰ on the pipe F¹², which leads to the centrifugal suction-pump 105 H, as shown in Fig. 2.

H' is the delivery-pipe, leading from the 110 centrifugal pump H, through which the dredging material and water are forced and delivered to any desired place by means of any suitable delivery or conveyer pipes.

I is a steam-engine, preferably located below deck, and i is the rotary driving-shaft on 115 said engine, to which shaft is secured a pulley I', from which leads a belt I'' to a pulley k on the horizontal shaft K, which shaft is located in suitable bearings below the deck A''. To said shaft are secured two pulleys K' K', from which lead belts K'' K'' to pulleys H'' H'' on the ends of the rotary pump-shaft H³, by which arrangement a rotary motion is imparted to the rotary pump-shaft in 120 the usual manner.

The agitator driving-shaft G is set in a rotary motion by intermediate connecting mechanism from the shaft K and engine I, as follows:

On the shaft K is a beveled gear K³, the teeth of which mesh in the corresponding gear L on a vertical shaft L', the upper end 130 of which is journaled in suitable bearings on the frame L'', secured to the deck of the scow, as shown in Fig. 2. To the upper end of said shaft is secured a spur-gear L³, the teeth of

which mesh in a similar spur-gear M, secured to a vertical shaft M', having its upper end journaled in a bearing M'', secured to the frame L'', and having its lower end journaled in a bearing secured to the elbow suction-pipe F. The axis of the shaft M' and vertical portion of the elbow F⁹ are made to coincide, as shown in Figs. 1 and 2.

M³ is a miter-gear secured to the shaft M', which gear meshes in a miter-gear M⁴, secured to the shaft m, located in bearings m' m'', secured, respectively, to the elbow-pipe F⁹ and horizontal suction-pipe F⁶, as shown in Fig. 2. The forward end of the shaft m is clutched to a short shaft m³ by means of a clutch m⁴, and the forward end of said shaft m³ is universally jointed to a horizontal shaft m⁵ by means of universal joints m⁶ m⁶, one of which can slide on the shaft on which it is located.

The shaft m⁵ is located in bearings m⁷, secured to the elbow-pipe F⁵, and to the forward end of the shaft m⁵ is secured a beveled pinion M⁵, the teeth of which mesh in the beveled gear G' on the shaft g.

In operating this my improved hydraulic dredging apparatus it is essential that the agitator while being rotated around its axis should be oscillated with the frame that carries it to the right and left in a circular path, and for this purpose I make use of mechanism as follows: To the shaft m is secured the miter-gear N, (shown in Fig. 4,) the teeth of which mesh in a similar miter-gear N', secured to a shaft N'', located in bearings in the frame B, and to said shaft N'' are secured the pulleys N³ and N⁴, with respective direct and cross belts n³ and n⁴ leading to the pulleys O³ and O⁴, loosely journaled on the shaft O'', journaled in suitable bearings on the frame B and provided with a friction-clutch O⁵, by means of which either one of the pulleys O³ or O⁴ may be connected to the shaft O'', according to the direction in which it is desired to drive the latter. To the shaft O'' is secured a beveled pinion O⁶, the teeth of which mesh in a beveled pinion O⁶, secured to a shaft O⁷, journaled in bearings in the frame B and provided in its lower end with the vertical pinion O⁸, the teeth of which mesh in a curved toothed rack-bar O⁹, secured in a suitable manner to the deck A'', as shown in Figs. 1, 2, and 4. By the employment of a curved rack O⁹ and the vertical pinion O⁸ the frame B and the mechanism carried by it is permitted freely to sag slightly downward, as may occur from time to time, without causing any binding between the pinion O⁸ and curved rack-bar O⁹, which is a constant source of trouble in machinery of this kind where the pinion and the curved rack are arranged horizontally instead of vertically, as shown in the drawings. The frame B is supported in its outer part by means of flanged wheels or rollers B', attached to the shaft B'', located in bearings secured to the frame-work B, which wheels are made to roll on a curved rail or bar a, secured to the top of the deck A.

The mechanism for raising and lowering the agitator and its telescopic tubes is constructed as follows: The miter-gear N on the shaft m meshes in the teeth of a miter-gear P' on the shaft P, journaled in suitable bearings on the frame B. To said shaft P is secured a pulley P'', provided with a belt P³, leading to a pulley P⁴, loosely journaled on a shaft P⁵, journaled in bearings on the frame B, said shaft having splined on it a friction-clutch P⁶, by means of which the rotary motion from the pulley P⁴ may be connected to or disconnected from the said shaft P⁵, as is usual in clutch devices. To the shaft P⁵ is secured a pinion P⁷, the teeth of which mesh in the teeth of a gear g, secured to the drum-shaft Q, journaled in bearings in the frame B. To the shaft Q are secured the hoisting-drums Q' Q'', from which lead the hoisting-ropes R R', guide-pulleys B³ B⁴, journaled in bearings on the laterally-extending upper frame-bar B⁵, as shown in Figs. 1, 2, and 3. The bar B⁵ extends in a lateral direction nearly the whole width of the scow, and has journaled to its ends the sheaves or pulleys B⁶, on which the ropes are guided downward around the sheave R' and secured in their upper ends to the outer ends of the lateral bar B⁵, as shown in Fig. 3. The pulley or hook of the sheave R' is connected in a suitable manner, preferably by means of ropes, chains, or links R'' R'' to the ears E⁵ on the valve-chamber E', as shown in said Fig. 3, and it will be seen that by this arrangement the agitator and telescopic tubes may be raised in a very simple and effective manner, the hoisting-ropes serving, also, as diagonal braces to take up any side strain to which the agitator and its pipes may be subjected during the operation of the machine. In lowering the agitator and its telescopic pipes as the dredging operation is continued downward, the friction-clutch P⁶ is moved away from the pulley P⁴, and the agitator and its telescopic tubes are allowed to sink downward, such downward motion being regulated by means of a brake-drum P⁸, secured to the shaft P⁵, and provided with a wooden brake-lever P⁹ and strap and lever releasing mechanism, as is common in brake devices for hoisting-machines.

In a machine of this kind it is essential that the agitator should be swung to one side, so as to bring it out of the water for the purpose of repairing it or its knives or for cleaning it from any débris that may have collected thereon, and for this purpose I provide one of the hoisting-drums (the one marked Q'' in Fig. 4) with a clutch Q³, adapted to slide on said shaft Q, and by means of which the said drum Q'' can be connected to or disconnected from the drum-shaft Q. If it is desired to swing the agitator and telescopic tubes to one side of the scow, as shown in dotted lines in Fig. 3, all that is necessary to do is to disconnect the clutch Q³ from the drum Q'', leaving the latter loose on the shaft Q, and as the drum Q' continues to rotate the hoisting-rope

R will be wound around, thus swinging the agitator to one side out of the water more or less, for the purpose mentioned.

- The different clutches are provided with 5 suitable levers, links, and locking devices, as is usual in the operation of such clutches, and they need not here be described in detail, as they are well known in the art and form no part of my present invention.
- 10 By means of the lateral beams B⁵ the hoisting-ropes are thrown into diagonal lines, so that they operate as braces to counteract side strain, while by the independent power-driven drums Q Q', connected with such hoisting-ropes, the agitator can be automatically raised 15 and lowered or swung to either side to bring the agitator out of the water. In this respect my invention differs from a dredging-machine wherein two manually-operated windlasses 20 connected with two cables are employed to haul the suction-pipe in the direction the work is to be done, and a third windlass or winch connected with a hoisting-cable is used to raise and lower the agitator in a right line.
- 25 Between the elbow-joint F⁵ and the bearing F⁸ of the shaft G is made the cylindrical trunnion F¹³, supported in a bar S, the lateral ends or extensions of which are connected by means of upwardly-projecting links or bars S' S' to 30 spring-buffers S'' S'', arranged on the top of the cross-bar B⁵, as shown in Figs. 1, 2, and 3, by which arrangement the outer end of the suction-pipe elbow F⁵ is properly supported during the operation of the machine.
- 35 The operation of the machine is as follows: By means of the engine I the box in the pump H is rotated as usual, and as the agitator is rotated against the side or bottom of the portion that is to be dredged below the water the 40 dredging material is drawn up from the water through the conical conductor C, tubular conductor E, valve-chamber E', telescopic tubes F F' F'', and pipes F⁵, F⁶, F⁷, and F¹², leading to the pump H and ejected from the 45 latter onto the land that is to be made or into scows by means of the pipe H' and suitable connecting-pipes. During the progress of the dredging process the frame B and the rotary agitator are oscillated toward the right and 50 left and the agitator lowered from time to time by mechanism, as hereinabove set forth, until the desired depth is reached, when the agitator and telescopic pipes are raised to the desired height, after which the scow or dredging 55 apparatus is brought into a new position, the agitator set in a rotary motion laterally to the desired depth for commencing the work and swung to the right and left and gradually lowered until the desired depth is reached, 60 and so on.

Having thus fully described the nature, construction, and operation of my invention, I wish to secure by Letters Patent and claim—

1. In a dredging-machine, the combination, 65 with an oscillatory frame and a suction-pipe, of a rotary agitator carried by a shaft at one

side of the suction-pipe and comprising a conical hood having upwardly and downwardly projecting cutters at its periphery, substantially as described. 70

2. In a dredging apparatus, a conical hood secured to a rotary shaft and having secured to its periphery upwardly and downwardly projecting cutters, substantially as and for the purpose set forth. 75

3. In a dredging apparatus, a rotating conical hood having curved wings or ribs C⁷ on its upper side and having secured to its periphery a series of upwardly and downwardly projecting cutters, substantially as and for the purpose set forth. 80

4. In a dredging apparatus, a telescopic suction-pipe and a vertically-adjustable rotary agitator-shaft arranged outside of the same, combined with a conical hood secured to said 85 agitator-shaft and having secured to its periphery a series of upwardly and downwardly projecting cutters, substantially as and for the purpose set forth.

5. The herein-described rotary agitator, consisting of a conical hood, a ring C', secured to the periphery of said hood and having its arms C'' C'' secured to a rotary driving-shaft, combined with upwardly and downwardly projecting cutters secured to the periphery of said 95 ring or hood, substantially as and for the purpose set forth. 90

6. In a dredging apparatus, a knife carrying hood secured to a rotary shaft arranged outside of the suction-pipe, combined with a 100 valve-chamber having a branch or conduit E, in which the upper end of said hood is journaled, and a telescopic suction-pipe, substantially as and for the purpose set forth.

7. In a dredging-machine, the combination, 105 with a vertically-adjustable shaft, of a rotary agitator comprising the ring C', the upwardly and downwardly projecting cutters D' D, provided, respectively, at their adjacent ends with the notches or recesses d' d, in which the 110 ring is clamped, and a ring D'', connecting the upwardly-projecting cutters, substantially as described.

8. In a dredging apparatus, a scow or vessel having secured to its deck a segmental 115 rack, combined with an oscillating suction-pipe and agitator-carrying frame having a vertical shaft O⁷ and a pinion O⁸ on the same meshing in the upright teeth of the said rack, substantially as and for the purpose set forth. 120

9. In a dredging apparatus, the combination, with a scow or vessel, of an oscillating frame mounted thereon and carrying a lateral beam B⁵, provided with guide-pulleys, two power-driven drums Q' Q'', mounted on a single shaft Q, journaled on the frame, a rotary agitator and telescopic suction-pipe, two hoisting chains or cables R, leading from the two drums over the pulleys on the lateral beam and serving as diagonal braces for and adapted 125 to raise and lower the agitator, and a clutch Q³, located on the drum-shaft, for disconnect- 130

ing one of the drums from the drum-shaft to automatically swing the agitator laterally out of the water, substantially as described.

10. In a dredging apparatus, a rotary conical hood having secured to it a series of downwardly-projecting cutters and a series of upwardly-projecting cutters having their upper ends united together by means of a ring D'', substantially as and for the purpose set forth.

In testimony whereof I have signed my name to this specification, in the presence of two subscribing witnesses, on this 20th day of February, A. D. 1890.

HENRY W. BROWN.
